UNITED STATES PATENT OFFICE.

WESLEY ROYCE, OF COLUMBUS, OHIO, ASSIGNOR OF ONE-HALF TO DAN-
FORTH H. ROYCE, OF SAME PLACE.

STEAM-ACTUATED VALVE.

SPECIFICATION forming part of Letters Patent No. 309,099, dated December 9, 1884.

Application filed June 11, 1884. (No model.)

To all whom it may concern:

Be it known that I, WESLEY ROYCE, of Columbus, Franklin county, Ohio, have invented a new and useful Improvement in 5 Steam-Actuated Valves, of which the following is a specification.

My present invention relates to improvements in the class of valve-movements for steam-engines, illustrated in Patent No. 10 261,485, for steam-actuated valves, granted to me on the 18th day of July, 1882, to which reference may be made for parts which my 15 said inventions possess in common. My improvements in this, as in the former case, concern those valve-movements of direct-acting steam-engines in which an auxiliary valve actuated from the main piston-rod governs a steam-actuated main valve or valve proper, which in turn controls the movements of the 20 engine-piston.

My invention relates to a new and useful construction and arrangement of the main and auxiliary valves with their respective inclosing chests or chambers, and their connecting 25 steam and exhaust passages.

The accompanying drawings show the parts in position for admitting steam in front of and discharging it from the rear of the piston.

Figure 1 is a side elevation of a direct-acting steam-engine embodying my improvements. Fig. 2 is a section on the line 2 2. Fig. 3 is a section on the line 3 3. Fig. 4 is a perspective view of the auxiliary valve. Fig. 5 is a side view of the valve proper. Fig. 35 6 is a section of said valve on line 6 6. Fig. 7 is a horizontal section of the valve proper. Fig. 8 is a similar section of a slightly-modified form of said valve, and of its inclosing chest.

40 For simplicity of representation, fastening-bolts and other customary details are omitted from the drawings.

A, B, and C may, respectively, represent the main cylinder, the piston, and the piston-rod of a direct-acting steam-engine.

From the upper part of the interior of the cylinder A, near its respective ends, proceed ducts D D', which, approaching one another and then turning upward, communicate with 50 a cylindrical chest, E, within which fits and slides my steam-actuated valve proper, F, of

correspondingly cylindrical shape, and just so much less length than the interior of said chest as to permit of the proper reciprocating action of said valve without liability of impact with the ends of the chest. Of the said ducts D D', each serves alternately as a steam and an exhaust duct. The interior of chest E communicates at its upper part, near the respective ends, by ducts G G', with a cylindrical chamber, H, located above and athwart the chest E, and having fitted within it a corresponding cylindrical valve, I, which operates by oscillation about its axis, produced by arm J, whose rod K derives its motion from the piston-rod, either by being bolted directly to it, as at k, or by other suitable means. Live steam enters chamber H at its top, which chamber and the chest E, respectively, communicate by exhaust-ports M 60 with the general escape-pipe N. In the present illustration each duct G G' is by turns a steam and an exhaust passage; but for some purposes I provide alongside of said ducts distinct exhaust-passages, such as represented in my aforesaid patent. The entire exhaust, in my present arrangement, taking place through the chest E, dispenses with customary exhaust-passage in the cylinder-wall. The valve proper, F, is traversed diametrically by an up-flared or funnel-formed tube, O, which constitutes part of the passage for the live steam to the main cylinder, communicating, for this purpose, with port P in top of chest E, through auxiliary valve I, with steam-supply pipe L. Two ports, f f', in bottom of valve proper, F, take turns in communicating one with one and the other with the other of the two ducts D D', the duct not then thus in communication communicating with and receiving steam from the tube O. A port, f'', through the side of the valve proper, F, communicates with the exhaust-passage M. A similar port or slot, f''', in opposite side of said valve, serves to "balance" it and to receive 70 a pin, Q, which prevents rotation of the valve. The auxiliary valve I is traversed diametrically by a passage, i, which carries steam directly downward through valve proper to the main cylinder. Branch passages i i'' take 75 turns in conveying steam through the ducts G G' to the respective ends of chest E for the 80 85 90 95 100

forward and backward propulsion of the valve proper. While such branch passage on one side of the auxiliary valve is conveying live steam to the duct on that side one of the passages $i''' i^{IV}$ on the other side is permitting exhaust of steam from the other duct into exhaust-port M' .

The above-described preferred form of my invention may be modified in non-essential particulars; for example, the live-steam tube-wall may, as in Fig. 8, be brought flush with the exhaust side of the valve proper, F, the exhaust-port M being coved, as at m , to afford free exit.

15 I claim as new and of my invention—

1. The cylindrical chest E, containing the cylindrical valve proper, F, crossed diametrically by the steam-tube O, and having the bottom exhaust-ports, $f f'$, and the side exhaust-port, f'' , in combination with the ducts D D' of the main cylinder, substantially as and for the purposes set forth.

2. The cylindrical chest E, containing the cylindrical valve proper, F, crossed diametrically by the live-steam tube O, and having

the bottom exhaust-ports, $f f'$, and the side exhaust-port, f'' , in combination with the ducts D D' on one side of said chest E, and with the steam-port P and the exhaust-port M on other sides of said chest, substantially as and for the purpose set forth.

3. In combination with the cylindrical valve proper, F, and with its cylindrical chest E, having the live-steam ducts G G' and the exhaust-ports M M', the transverse cylindrical chamber H, having the cylindrical auxiliary valve I, containing the diametrical branched passage $i i' i''$ and the exhaust-passages $i''' i^{IV}$, formed and operating as set forth.

4. The hollow cylindrical steam-actuated valve proper, having the diametric central tube, O, for live steam, the exhaust-ports $f f'$, f'' , and the balancing port or slot f''' , containing the guide-pin Q, substantially as set forth.

In testimony of which invention I hereunto set my hand.

WESLEY ROYCE.
